UNITED STATES PATENT OFFICE

HARRY W. KULP AND MARTIN C. DELLINGER, OF LANCASTER, PENNSYLVANIA

VALVE-SPRING LIFTER

Application filed December 12, 1928. Serial No. 325,462.

This invention relates to valve-spring lifters and compressors such as shown and described in our Patent No. 1,359,814 granted November 23, 1920, on which the present invention is an improvement.

In a popular make of automobile, known commercially as the Ford Model A, that has gone into practically universal use in this country recently it is necessary to remove the valve-stem bushings before the valves with their stems may be removed for replacement or preparatory to grinding, and before the bushings can be removed it is necessary to bodily remove the valve-springs which also bear against said bushings, and of course after the valves with their stems and their respective bushings have been replaced it is necessary to reinsert the valve-springs, raise or lift or compress their lower ends and thereafter apply the lower spring cups or retaining means to the respective valve-stems, and the present invention is primarily intended for use in connection with this make of automobile, as well as others in which similar operations are necessary.

The primary objects of the present invention are, to provide a parallel jaw movement valve-spring lifter or compressor movable in contact with a supporting surface or surfaces, either plane or of other conformation, toward and from the axis of the valve stem and tiltable with relation thereto while applied to and lifting or compressing the valve spring to various positions or degrees of compression as well as while positioning said spring incident to the replacement or insertion thereof; and to provide in such a valve-spring lifter or compressor a jaw of such construction that while spanning the valve-stem it will interlock with the coils of the spring, so serving the dual functions of a lifting or compressing jaw and of a gripping, carrying or positioning jaw both in the removal and replacement of the valve-spring.

In the accompanying drawings:

Figure 1 represents a side elevation of a valve-spring lifter embodying our invention as operatively applied to a valve-spring and bearing against the opposed adjacent portion of the crank case, shown fragmentarily

and conventionally, the parts being moved to lift or compress the spring preparatory to removal to the lower spring cup or retainer O;

Figure 2, a sectional view on the line 2-2 of Figure 1;

Figure 3, a view similar to Fig. 1, showing the parts in the last stages of the removal operation, or the first stages of the replacement or insertion operation, the tongue 3 of the tool being in contact with the crankcase adjacent the side thereof; and

Figure 4, a top plan view of the tool showing particularly the conformation of the gripping, or carrying and lifting or compressing jaw 4.

Referring now in detail to the drawings, the tool comprises a stationary preferably sheet metal beam 1 approximately U-shape in cross-section, a movable beam 2 also preferably of sheet metal and approximately U-shape in cross-section, said beams being connected for parallel movement by crossed links A and E respectively pivotally connected by pivot pins D and F to the forward portions of the beams 2 and 1 and respectively slidably pivotally connected to said beams 1 and 2 by pivot pins C and G respectively extending through the rear portions of their respective links A and E and slidable in slots C' and G' in the sides of the respective beams 1 and 2, said links A and E being pivotally connected together in their crossing medial portions by a transverse pivot pin H, and the rear end of link A being continued upwardly and rearwardly as a horn to have rigidly secured thereto a handgrip or handle B to cooperate with the rear portion of the beam 1 in the single-hand operation of the tool, the construction thus far described being the same as set forth in the above identified patent to which reference is made for a more detail construction.

K designates the usual guide for the tappet L for engaging and raising the valve-stem M on which is arranged the valve-spring N cooperating with the spring cup or retainer O interlocking with the enlarged lower end of the said valve-stem M so as to connect said spring and stem whereby the latter will force

said stem M toward the tappet L, all as shown, for instance, in more detail in Patent No. 1,640,118 granted August 23, 1927 to Henry Ford, said tappet-guide K being integral with the adjacent upper portion of the crank-case J, which may have an outer edge flange J' as shown in Figs. 1 and 2.

The forward end portion of the beam 1 is spread, reduced in width and bent abruptly 10 downwardly at right angles to the beam 1 to form a supporting wide-footed dull edged supporting tongue adapted to serve as a skid or skate to move in sliding contact with the upper face of the top of the crank-case J adjacent the tappet-guides K and while under the load of the spring while the latter is subject to varying degrees of compression and while the compression is being either increased or decreased by the movement of the 15 handle B toward or from the beam 1, said tongue 3 making a wide supporting contact with the top of the crank-case J in a direction transverse of the tool as a whole, thus preventing any tendency of the tool to twist as a whole 20 about its axis when under the load of the spring N and so guarding against its twisting or being "kicked" out of position, and at the same time making a relatively narrow edge contact with said crank-case J in the longitudinal direction of the tool as a whole, whereby said tool may be tilted through a 25 wide range of positions on said edge as a fulcrum point toward or from the guide K, stem M and spring N both during and after the operation of the links A and E, such tilting greatly facilitating the removal and insertion of the spring N, it being remembered 30 that such operations must be performed in a relatively small opening in rather cramped quarters.

The forward end of the beam 2 is flattened out, spread, extended forward, bifurcated to provide a jaw 4 to receive and fit about the valve-stem M and adjacent said bifurcation it is formed with a groove 4' to seat a coil or helice of the spring N, the jaw as a whole being of relatively thin sheet metal and the lower face thereof being convex in cross-section, complementary to the groove 45 in the upper face, so as to make a snug tight fit between, and in engagement with the opposed faces of, adjacent helices of the spring which thus interlocks with said jaw 4 and holds itself therein so that an endwise movement of the beam 2 with its jaw 4 thus interlocked with the spring N will result in a lateral movement of the lower portion of the spring N, as illustrated in Fig. 3, and in the 50 spring N being retained in said jaw 4 when withdrawn from position. Such endwise movement of the jaw 4 involves the movement of the tool as a whole, of course, and may be due either to sliding the tongue 3 over and in contact with the crank-case J, or tilting 55 the tool as a whole on the edge of tongue 60 65

3 lengthwise of the tool, or by both said sliding and tilting movement simultaneously.

Having thus described our invention, what we claim as new and desire to secure by Letters Patent is:

1. A valve-spring lifting tool comprising a pair of relatively movable members, means for moving said members with relation to each other, and means for maintaining said members substantially parallel to each other in all relative positions throughout their range of relative movement, in combination with a tongue rigid with and depending from one of said members and adapted to engage a supporting surface and move in contact therewith and tilt about its point of engagement with said surface in one plane while the tool is operatively engaged with and under the load of the spring, whereby the members may be moved relatively to each other and the tool as a whole may be tilted into a number of different positions with one hand and while operatively engaged with, and under the load of, the valve-spring. 70 75 80 85 90

2. A valve-spring lifting tool comprising a pair of relatively movable members, means for moving said members with relation to each other, and means for maintaining said members substantially parallel to each other in all relative positions throughout their range of relative movement, in combination with a tongue rigid with and depending from one of said members and adapted to engage a supporting surface and move in contact therewith and tilt about its point of engagement with said surface in one plane while the tool is operatively engaged with and under the load of the spring, whereby the members may be moved relative to each other and the tool as a whole may be moved about 95 100 105 110 115 120 125 130

and tilted into a number of different positions with one hand and while operatively engaged with, and under the load of, the valve-spring, and a bifurcated jaw rigid with the other member and having a grooved portion to receive a helix of the spring and to interlock with and be gripped by and between the opposed adjacent portions of the helices of said spring between which it is thrust.

3. A valve-spring lifting tool comprising a pair of members at least one of which is movable relative to the other, a tongue rigid with and depending from the other member at an abrupt angle and adapted in operative position to engage and be supported by a supporting surface and adapted when under the load of the valve-spring to slide in contact with said supporting surface and tilt in contact therewith in a plane parallel to the longest dimension of said tool and formed with a long surface extending in a direction transverse to said plane and contacting with said supporting surface in operative position, whereby twisting of the tool as a whole

about its axis when under the load of the valve-spring will be prevented, and a pair of hand-grips arranged to be together gripped in one hand of the operator and at least one 5 of which is movable relative to the other to move said movable member, whereby said member may be moved, and said tool as a whole may be moved about and tilted, by the operator with one hand to all positions necessary in the raising, removal and replacement of the valve-spring.

4. A parallel-jaw movement type of valve-spring lifting tool comprising an upper member, a lower member, and means for causing 15 relative movement between said members, in combination with a tongue depending from the forward end portion of the lower member and having a bottom edge extending transversely of the tool for the width of said tongue, and a bifurcated jaw rigid with and extending from the upper member forward beyond said tongue and grooved adjacent its bifurcation to interlock with the helices of 20 said valve-spring between which helices it is adapted to be thrust.

5. A parallel-jaw movement type of valve-spring lifting tool comprising a pair of relatively movable members, and a jaw carried by one of said members, in combination with 30 a tongue depending from the forward end of the other member to the rear of said jaw and adapted to contact, in operative position, by its bottom end, with, and slide on, a supporting surface when the jaw is engaged with 35 a valve-spring during the lifting, removal and replacement of said spring.

6. A valve-spring lifting tool comprising a bifurcated thin sheet metal jaw having a curvilinearly bent portion conforming to the 40 form of a spring helix and having substantially parallel upper and lower faces and adapted to be engaged on said upper and lower faces by the opposed face portions of two adjacent helices of a helical spring.

45 7. A valve-spring lifting tool comprising a bifurcated thin metal jaw having substantially parallel curvilinear portions disposed one above and the other below the respective normally horizontal faces of said jaw respectively and in vertical registry with each other at all points, the distance between the upper and lower faces of said curvilinear portions at all points being approximately the same as the thickness of the adjacent portions of 50 said jaw, and said curvilinear upper and lower face portions being adapted to be inserted between, engaged by, and gripped between, the opposed face portions of two adjacent helices of a helical spring.

60 In testimony whereof, we have signed our names to this specification at Lancaster, Pennsylvania, this 10th day of December, 1928.

HARRY W. KULP.
MARTIN C. DELLINGER.
